(57) **CLAIM**

The ornamental design for a portable electric circular saw, as shown and described.

DESCRIPTION

FIG. 1 is a front perspective view of a portable electric circular saw in accordance with our new design;

FIG. 2 is a rear perspective view of the portable electric circular saw in accordance with our new design;

FIG. 3 is a front elevational view of the portable electric circular saw in accordance with our new design;

FIG. 4 is a rear elevational view of the portable electric circular saw in accordance with our new design;

FIG. 5 is a top plan view of the portable electric circular saw in accordance with our new design;

FIG. 6 is a bottom plan view of the portable electric circular saw in accordance with our new design;

FIG. 7 is a left side elevational view of the portable electric circular saw in accordance with our new design;

FIG. 8 is a right side elevational view of the portable electric circular saw in accordance with our new design; and,

FIG. 9 is a rear perspective view, similar to FIG. 2 of the portable electric circular saw in accordance with our new design illustrating a state in which rechargeable batteries are attached to the portable electric circular saw.

The broken line showing of environment structures in the drawings forms no part of the claimed design. The portions within the broken line form no part of the claimed design.

1 Claim, 9 Drawing Sheets
